UNITED STATES PATENT OFFICE.

IRVING W. RICE, OF NEW YORK, N. Y.

DESIGN FOR A DISPLAY-CASE.

59,870.

Specification for Design.

Patented Nov. 29, 1921.

Application filed December 5, 1919. Serial No. 342,841. Term of patent 7 years.

To all whom it may concern:

Be it known that I, IRVING W. RICE, a citizen of the United States, and a resident of New York, county and State of New York, have invented a new, original, and ornamental Design for Display-Cases, of which the following is a specification, reference being had to the accompanying drawings, forming a part thereof, in which—

Figure 1 shows a plan view of a display case of my new design and Fig. 2 is a cross-section on the line 2—2 of Fig. 1.

My invention relates more particularly to display cases for manicure implements and accessories.

Referring to the drawings, it will be seen that my ornamental design comprises a sub-

stantially rectangular case which is provided with a plurality of compartments, some of which extend longitudinally and others transversely of the case; one of the longitudinal compartments being longer than the others by the width of the transverse compartments. The display case is covered by a single plate of glass of a size to over-hang the walls of the case uniformly on all sides. Numbers are preferably placed on the glass cover plate, over each compartment which may indicate the price of articles in the respective compartments.

I claim:—

The ornamental design for a display case as shown.

IRVING W. RICE.
